UNITED STATES PATENT OFFICE

ALBERT C. HOLT, OF MANGHAM, LOUISIANA

KIDDIE PROPELLED MERRY-GO-ROUND

Application filed November 14, 1930. Serial No. 495,758.

My present invention has reference to a merry-go-round for use by children, and my primary object is the provision of a device of this character which will afford amusement and healthy exercise to the operators of the apparatus.

A still further object is the provision of a merry-go-round that is manually operated by the children occupying the seats thereof in a manner whereby the arms, feet, legs and as a matter of fact every part of their bodies is exercised in the operation of the apparatus and which apparatus is of a simple, strong and sturdy construction that may be cheaply erected and thereby reduce the cost of production, the manual operating means avoiding the necessity of a motor or other power driving mechanism and consequently reduces the cost of operation.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a side elevation of a child's merry-go-round in accordance with this invention, parts being in section.

Figure 2 is a top plan view of a sufficient portion of the apparatus to illustrate the invention.

Figure 3 is a plan view illustrating a slight modification, which principally resides in the reduced number of seats and in both pedal and lever means for operating the apparatus.

Figure 4 is a central longitudinal sectional view through one of the cars to illustrate the operating means similar to that disclosed by Figure 3 but in which the occupants face each other.

Figure 5 is a sectional view approximately on the line 5—5 of Figure 4.

Figure 6 is a front elevation of one of the combined foot and pedal operating devices illustrating a further modification.

55

Figure 7 is a side elevation thereof.

Figure 8 is a perspective view of one of the foot pedals.

Figure 9 is a sectional view approximately on the line 9—9 of Figure 2.

60

Preferably and as disclosed by Figure 1 of the drawings I embed in a concrete block 1 which in turn is embedded in a ground surface 2 the lower and preferably square end 3 of a post 4 which is round in cross section. The post is also preferably in the nature of a tubular member of sufficient strength to withstand the strain to which it is subjected and if desired the post 4 may be formed with the end 3 therefor. The top of the post is closed by an ornamental cap 5 and this cap may have attached thereto the staff for a flag or the said staff may be received in the hollow post 4.

65

Fixed on the post 4, above the concrete block 1 there is a disc 6 that provides a track. Preferably this track is of wood and also preferably the periphery of the track is bound by a metal ring. Also if desired the under face of the track may be reinforced by metal elements but in order to obtain a sufficient friction between the upper face of the track and the operating wheels hereinafter to be described the wooden face on such disc is preserved.

70

Between the bottom 3 of the post 4 there are angle brace rods 7 that have straight ends through which the securing means are passed.

80

The track on its upper face is centrally provided with an opening that has secured therein the tubular member or collar 8 that is secured to the post 4 by means 9 and arranged around the post for turning thereon and contacting with the upper end of the tubular member 8 of the track there is a sleeve 10. There are preferably anti-frictional bearings between the sleeve 10, the post 4 and the collar 8 and the outer periphery of the collar 8 has rigidly secured thereto and radiating therefrom T-irons in the nature of spokes 11. In

85

90

95

100

the showing of Figures 1 and 2 of the drawings ten of such spokes are provided, although the sleeve may be provided with any desired number of such spokes. The spokes have riveted or otherwise secured thereto upwardly directed angle brace rods 12 and these brace rods are secured to the under face of a flanged disc member 13 that is revoluble around the post 4.

On the under face of certain of the spokes 10 11 there are secured cross sectionally U-shaped brackets 14 whose arms depend and are directed toward the circular track 6 and between the said arms of the brackets there 15 are journaled shafts 15 carrying rollers 16 which frictionally contact with the upper face of the track 6. Preferably the bearings for the shafts 15 are spring influenced to bring the rollers 16 into proper frictional contact with the track. The shafts 15 are comparatively short and carry on their outer ends clutch heads 17, slidable in spring influenced clutch members 18 that coengage with the clutch members 17, the said members 18 being 20 splined for movement on the ends of the operating shafts 19 of the apparatus and the shafts 19 have their inner ends journaled through bearing brackets 20 which are of angle formation and which are fixed to the outer arms of the brackets 14.

The spokes at the outer ends thereof are connected to a flanged ring 21, and the spokes, inward of the ring are connected together and braced by struts 22, the said struts being preferably in the nature of angle irons. On the upper faces of certain of the struts there are secured angle brackets 23 to which are connected brace rods 24 that are in turn connected to the flange of the disc member 13. The 40 struts and peripheral ring hold the spokes in proper spaced relation to each other and the brace members 12 and 24 effectively sustain the spokes in horizontal position and prevent any tendency of downward sagging thereof.

Between certain of the struts 22, spokes 11 and peripheral ring 21 there are secured the seats 25 for the operators. The seats are provided with backs and are disposed a slight but suitable distance away from the oppositely directed cranks 26 and 27 formed on the portions of the shafts 19 arranged directly below the said seats 25. The outer ends of the shafts 19 are journaled through depending brackets or plates 28, carried by the peripheral ring 21 and outer brackets or plates 29 secured to and depending from the strut braces 22, there being suitable means 30 for holding the shafts 19 from longitudinal movement and the outer plates 28 have fixed thereon the angle ends of steps 31 whereby the operator may arrange him or herself in the seat. The straight connected portions of the shafts 19, between the cranks 26 and 27 have pivotally mounted thereon foot pedals 32. 60 65 70 75 80 85 90 95 100 105 110 115 120 125 130

for the clutch elements between the cooperating shafts 19 and 15 may be in the nature of housings for enclosing said clutch elements.

The outer arms of the inverted U-shaped brackets 14 have secured thereon depending plates 33, and to each of these plates there is pivoted, as at 34, an angle rod or lever 35. The lower arm of each of the members 25 is provided in its end with a brake shoe 36, and the outer arms of the angle brake members 35 have connected thereto links 37 which in turn are connected to hand levers 38 which have their lower ends pivoted, as at 39, to plates 40 which may be secured to the depending plates 29. Obviously by pulling the lever toward the seat the operator will apply the brake, causing the shoe thereof to frictionally contact with the periphery of the track and thereby stop the rotation of the apparatus should the operator find him or herself in danger or when it is desired that the apparatus be stopped for other passengers.

It will be apparent that by operating the foot pedals 32 the shafts 19 will be caused to turn and impart a similar movement to the wheels or rollers 16 so that the children occupying the seats 25 are afforded not only amusement but a healthy exercise. Should the occupant of any of the seats find his or her strength waning it is merely necessary that pressure be exerted upon the pedals to hold the shafts 19 from turning which will cause the ratchet element or head 18 to ratchet over the fixed ratchet element 17.

In the modification illustrated by Figure 3 the construction is substantially similar to that previously described, except that the sleeve 10 has secured to the opposite sides thereof the center of two elongated spokes 41. These spokes on the outer ends thereof support hollow bodies 42. The bodies may be of any desired shape but in the showing of the drawings represent miniature aeroplanes. The cockpits of the aeroplanes are provided with spaced seats 43-44 and the opposite crank portions 45 and 46 of the operating shafts have connected thereto oppositely directed links 47, respectively. These links are arranged at opposite downward angles with respect to each other, and the ends thereof are pivotally connected, as at 48, to the lower ends of levers 49 which are pivotally supported, as at 50, to plates carried by the framework of the bodies 42. The links or the pivot 48 for the links have journaled thereon foot pedals 51. In this construction the levers are grasped by the hands of the operators whose feet rest on the pedals 51 and also in this construction both the feet and arms of the operator are brought into use for turning the cranks of the operating shaft for the wheels or rollers 16. With this form of apparatus every portion of the child operator's body is subjected to movement and, therefore, a child is afforded

healthy exercise as well as amusement. In Figures 4 and 5 the construction is similar to that just described except that the seats face each other in counterdistinction to the reverse arrangement disclosed in said Figure 3.

In Figures 6 and 7 the operating levers have their upper ends provided with lateral handles 52 and the pivots which connect the lower ends thereof to the links 54 are in the nature of elongated rods 53 which extend laterally from the sides of the straight body of the levers and which provide foot pedals. The levers have their short shafts or pivots suitably journaled in means 55 connected to and depending from the body of the cars.

It is thought the foregoing description will fully and clearly set forth the construction and advantages to those skilled in the art to which such invention relates so that further detailed description will not be required.

Having described the invention, I claim:

A merry-go-round comprising a circular disc, mounted at a fixed position, a post passing centrally through the disc, a brake band 25 circumscribing the periphery of the disc, a sleeve journaled upon the post, spokes radiating from the sleeve, brackets carried by the spokes and disposed above the disc, rollers journaled in the brackets and bearing upon 30 the upper surfaces of the disc, shafts journaled below the spokes and having pedal cranks, interengaging clutch members carried by the shafts and the axles of the rollers, a brake lever pivoted to one of the brackets 35 and having a shoe adapted to engage the brake band, a second lever journaled in the vicinity of the outer end of one of the shafts and a rod operatively connecting said levers together.

40 In testimony whereof I affix my signature.
ALBERT C. HOLT.
